K. C. HALE

TROLLEY WIRE HOLDING RAIL

Filed June 26, 1922

Inventor

Kenneth C. Hale

By Whittier, Hubbard & Whittier
+ Belknap Attorneys

UNITED STATES PATENT OFFICE.

KENNETH C. HALE, OF DETROIT, MICHIGAN.

TROLLEY-WIRE-HOLDING RAIL.

Application filed June 26, 1922. Serial No. 570,814.

To all whom it may concern:

Be it known that I, KENNETH C. HALE, a citizen of the United States of America, residing at Detroit, in the county of Wayne and State of Michigan, have invented certain new and useful Improvements in Trolley-Wire-Holding Rails, of which the following is a specification, reference being had therein to the accompanying drawings.

10 The invention relates to electric trolley rails designed for use under bridges and in other places where the clearance above the car is restricted. It is usual to provide in such places a channeled conductor rail distinct from the trolley wire, which forms an electrical connection with the flanges of the trolley while passing under the structure. With my improved construction the trolley wire passes uninterruptedly beneath the 20 structure in a position to be traversed by the trolley and is supported in such position by a continuously extended rail secured thereto. More particularly, the construction is one in which the supporting rail is a 25 rolled section having flanges adapted to be closed about the section of the trolley wire so as to be securely attached thereto. The invention therefore consists in the construction as hereinafter set forth.

30 In the drawings:

Figure 1 is a longitudinal section showing a bridge structure to which my improvement is applied;

Figure 2 is a cross-section thereof;

35 Figure 3 is a cross section of the rail as first rolled before engagement with the trolley wire.

A is the bridge structure, which is indicated as being formed of concrete but which 40 may be of any suitable construction. B is a strip of impregnated wood or other insulating material, which is secured to the bottom of the bridge A and extends between the opposite sides thereof. C is a rail, preferably a rolled section having a base flange D, a depending central web E, thin flanges F projecting oppositely from the lower end of the web section, and a groove G between said flanges forming a seat for the trolley wire. This rail is arranged to extend continuously from one side of the bridge to the other, the flanges D being secured to the strip B. The trolley wire H is first placed

in the groove G, after which the thin flanges F are bent to embrace the same, as shown in Figure 2. The operation of bending the flanges may be performed by any suitable tool and, when complete, will hold the wire from displacement but with its lower face projecting below the rail. Thus the trolley passes from the portions of the wire outside of the bridge directly into engagement with the rail C, the depth of the web of which is sufficient to permit the trolley to continue into engagement with the wire while passing under the bridge. However, the fact that the rail is continuous will form of this portion of the trolley wire a rigid structure.

What I claim as my invention is:

1. The combination with a trolley wire, 70 of a rail for supporting said wire while passing beneath a restricted clearance, said rail having a continuous web forming a rigid bearing for the wire.

2. The combination with a trolley wire, 75 of a rail for supporting said wire while passing beneath a restricted clearance, said rail being provided with a continuous web affording a rigid bearing for the wire, and laterally extending flanges embracing the wire to 80 retain the same.

3. The combination with a trolley wire, of 85 a rail for supporting said wire while passing beneath a restricted clearance, comprising a continuously extending web portion forming a rigid bearing for the wire and relatively thin laterally extending flanges crimped about the wire to retain the same.

4. The combination with a trolley wire, 90 of a rail for supporting said wire while passing beneath a restricted clearance, comprising a rolled section having a base or securing portion, a depending web, and laterally extending flanges at the lower end of said web crimped about the wire to retain the 95 same.

5. The combination with a bridge structure and a trolley wire, of a support for said trolley wire comprising a rail secured to said bridge structure and extending from 100 one side thereof to the other and having means for gripping the trolley wire continuously throughout its length.

In testimony whereof I affix my signature.

KENNETH C. HALE.
